DESIGN FOR A COMBINED TOY BUILDING AND CONTAINER BOX

John Lane, Kirtland, and Alfred C. Schneider, Westlake, Ohio, assignors to Keeler & Dunkel, Inc., Cleveland, Ohio, a corporation of Ohio
Original design application Apr. 15, 1966, Ser. No. 1,907.
Divided and this application Jan. 18, 1967, Ser. No. 5,464

Term of patent 14 years

(Cl. D34—15)

Fig. 1

Fig. 2

Fig. 3

Fig. 4

FIG. 1 is a front perspective view of a combined toy building and container box embodying our new design;

FIG. 2 is a rear perspective view thereof;

FIG. 3 is a top plan view thereof; and

FIG. 4 is a side elevation view of the right side of the design shown in FIGS. 1 and 3.

The broken line showing of a building is for illustrative purposes only.

This is a division of design application Ser. No. D. 1907, filed Apr. 15, 1966, now abandoned.

We claim:

The ornamental design for a combined toy building and container box, substantially as shown and described.
